UNITED STATES PATENT OFFICE.

GARRETT WALL HOPKINS, OF TRUMANSBURG, ASSIGNOR OF ONE-HALF TO
GEORGE V. BENJAMIN, OF ITHACA, NEW YORK.

RAILWAY SNOW-PLOW.

SPECIFICATION forming part of Letters Patent No. 316,972, dated May 5, 1885.

Application filed December 20, 1884. (No model.)

To all whom it may concern:

Be it known that I, GARRETT WALL HOPKINS, a citizen of the United States, residing at Trumansburg, Tompkins county, New York, 5 have invented an Improved Railway Snow-Plow, of which the following is a specification.

My invention relates to that class of snow-plows that excavate and transport the snow from deep cuts or banks, as well as serve for 10 the thinnest fall of snow; and the nature of my invention will be apparent as I describe its several parts.

Figure 1 is a side elevation of my snow-plow standing on a railway-track. Fig. 2 is a trans- 15 verse sectional ground plan. Figs. 3 to 9 are detached detail views.

In the figures, *a* is a portion of a railway-track on which my plow stands, and *b* is a hard-wood sheathing, (represented in detail in 20 Fig. 4,) sufficiently strong to sustain the plow, and by its sliding surface aid in the return of the plow if derailed. Next above this, in Fig. 1, are openings *c*, four in number, in which are slide boards or frames, (indicated 25 in detail in Fig. 6, and in the ground plan, Fig. 2,) which slide out of their places two, three, or four feet, and are hinged to the perpendicular partition-slides *c''*. The horizontal slides *c'* and the perpendicular slides *c''* 30 are moved out of their concealment in the plow structure together.

In occupation of the middle parts of the plow is a series of semicircular snow-holders, *d*, on each side of the plow, fast to the inclined shafts *d'*, on the top of which shafts are 35 levers *e*, by which the semicircular snow-holders are turned out of their position in the plow-structure and made to cut into the snow compacted on the sides of the plow when it is 40 run or rammed into a snow obstruction. In Fig. 2 these holders are represented in various positions. Three, *d''', d'*, and *d''*, are closed in the plow—their position when the plow is run into a snow-bank. The holder *d''* is nearly 45 rotated outward to its full extent. The holder *d'''* is in the position of being fully loaded, the holder *d''* to be half-loaded. The other two spaces are represented empty, that the relations of the bottom slides may be seen.

50 It is apparent that my design is to make any number of holders on each side of the plow and fasten them on shafts journaled near the outer

edges of the sides of the plow, conceal them in it, and, when the plow is run into a bank of snow, by the levers *e*, move them outward into the 55 snow, cutting off the snow and loading the holders, and when they are thus filled rotating them back into the inside of the plow structure, ready to be transported out of the bank when the locomotive draws backward 60 the plow. Thus the snow is cut into by the semicircular holders leaving the snow in the intervals between the holders not yet detached from the bank.

It will next be noticed that in Fig. 1, just 65 below the handles *e*, are the second set of handles or levers, *e'*. These are fast to hollow shafts put over or about the shafts *d'*. They connect with the doors *e''*, and when the holders, as at *d''*, are outward and full of snow, 70 these doors, in the position seen in Fig. 1, are against the snow now in the holders. Then the levers *e* and *e'* are turned simultaneously backward, and thus the holders and their load of snow are moved into the inside of the 75 plow structure, and, there being, as in Fig. 1, four holders on each side of the plow, each eight feet in diameter, there will be thirty-two 80 feet of the snow obstruction cut out and loaded into the plow, and so on if the plow is constructed with a larger number of holders; but spaces are left between the holders not cut out. These are removed by the perpendicular slides *c''*, concealed in the plow. They 85 are run out by the hand-wheels *g*, whose shafts operate pinions and racks on the slides. Thus the turning of the wheels moves the slides into the middle of these spaces of snow, cutting them in their middle portions, so that by backing the locomotives and snow-plow or 90 running them forward they are easily broken down by these slides. These slides are braced by chains or folding rods *c'''* at their tops, and thus are held firmly when run out. A pair 95 of slides is thrust out, one slide on each side of the plow, by one wheel *g*, pinion, and two racks. In connection with these slides being thus run out, because hinged to them, the horizontal slides are also run out. They are made somewhat triangular in shape, as seen in Fig. 6, and have projections *h*, by which they are hinged to the outer ends of the perpendicular slides. Their other ends have slots *h'*, in which studs or bolts play, so made 100

that when the perpendicular slides are run out by the hand-wheels g , carrying the horizontal slides, the bolts h tighten just at the instant the slides are fully out of the plow, 5 and thus the slides act as braces of the lower ends of the perpendicular slides, and there being two horizontal slides to each holder, one on each side, the bracing is made both ways. The use of these lower or horizontal 10 slides is to catch, hold, and transport the snow left uncut by the holders when the running backward or forward breaks it down.

The holders cut into the snow-obstacle spaces represented on the scale of four feet on each 15 side of the plow, and the slides remove the partitions of snow left between the cut-out spaces.

The plow has three sets of timber braces to stiffen it, which, as they are carpentry, need 20 only be named: first, a firm longitudinal one between the two series of holders in the middle of the plow; second, transverse bracing, partially shown in Fig. 5; third, a deck transverse bracing (not represented) of the deck i 25 of Figs. 5 and 7.

A top rail, j , runs about the top of the plow. A caboose-lookout, j'' , and a loose fender, f' , are over the plow ends $j^1 j^2$, and are adjustable to each end of the plow, which is represented 30 on the scale of sixty-six feet in length, that being the usual length of a passenger-car. It will be longer if five to ten holders are used on each side of the plow. A dotted line, f , in Fig. 2, shows the snow-line about the 35 plow and the cut made by the plow.

The plow-points are shown in two forms—one, j'' , of metal over wood, sharp, with projecting metallic cutting lower edges, k , and a top cutting-edge, k' . Its design is to cut and 40 break up the tough, not deep, compacted snow off of prairies, and is adapted to any not deep snow anywhere. It is an additional point to the usual point shown. The form at j''' is of wood and metal-edged, with a long slide-surface, k'' , suited to hold down the end of the 45 plow in hard snow. The rest of the ends are wood, side turning-points for deep banks of light snow, without the use of the holders, rendering my plow suited to all snow emergencies, and serviceable for all snows that any 50 plow can be used in.

In Fig. 5 it will be observed that the shafts d' of the holders are inclined outward at their tops. This is for two purposes: First, to cut 55 the excavation through the snow obstacle with sides wider at the top than at the bottom; and, second, to cut the excavation on each side of the track down deeply, even as deep as the top of the rails.

60 In unloading, the locomotives draw the loaded plow backward or push it forward to any unobstructed place, when by moving the slides backward into the plow the loads held by them are discharged, and by reversing the 65 levers e that move the doors e'' these doors, revolving on their shafts, push the snow out of the holders, aided by their inclined position.

At the top of the holders a triangular top corner-piece, e' , is fast to the holders. Its use is to ease the burden of the doors by not 70 pushing all the snow at one time out of the holders. The repetition of the motion of the doors discharges the snow, not thrust out by their first motion.

By the figure (Fig. 3^a) the top of the holder on its shaft d' , with the doors e'' partially revolved, is shown. By Fig. 3^b a perpendicular elevation of a holder is represented, the doors being omitted, and a lever on a pipe-socket shaft. This lever is the top- 75 plate lever, e'' . The lever e operates the inside solid shaft, d' , by its attachment to the base-plate of the holder. Fig. 3^c is a view of the doors fast to a pipe-shaft, e^6 , operated 80 by the lever e' . Fig. 5 is a transverse sectional view representing the holders d on their shafts d' , the deck i , the hard-wood sheathing b , top rails, j , the middle timber bracing of carpentry, n , the cross-bracing n' , and the deck-bracing n'' , the top joists, n''' , 90 and the bottom joists, n^4 , and the base-purlins n^5 . Fig. 4 represents the hard-wood bottom sheathing of the plow, with openings for the wheels on which it moves. Fig. 6 95 represents one of the horizontal slides detached; Fig. 7, the two perpendicular slides, one to the right hand by full lines and extended outward by the rack c'' , fast to it, and the other, the left-hand one, partially by full lines and partially by dotted lines, as being 100 under the right-hand slide. The rack c' is seen in full lines. Fig. 9 shows the same thing from above. Their position is seen at c^6 and c^6 , Fig. 2, both in and out of the plow. Fig. 8 represents the two handles $e e'''$ meeting 105 at their ends, the lever e being fast to the solid central shaft d' , and the bottom lever, e'' , to the outer short pipe-shaft, e^5 . The middle pipe-shaft or door-shaft is marked e^6 .

Other things are believed to be clear by 110 what has been said and represented, so as to need no further remark.

What I claim in a snow-plow is—

1. The semicircular chambers or snow-holders suspended on shafts on the sides of the 115 plow, which, when the plow is run into a snow obstruction, are concealed in the plow structure, by their shafts are turned outward, cutting out portions of the obstruction, loading themselves with the thus detached snow, and 120 are rotated, with their loads, into the plow, as set forth.

2. In combination with the semicircular snow-holders, the doors hinged to central shafts that close the mouth of the holders 125 and by their rotation discharge the snow, as set forth.

3. The inclined shafts and snow-holders, the inclination being given them to produce inclined walls of snow in the excavation, and to 130 aid in unloading the holders.

4. The perpendicular slides in the plow structure, which are run out into the partitions of undetached snow between the spaces

cut out by the holders, and which break down the partitions and trim the sides of the excavation when the plow is run either way out of the obstructing snow.

5 5. The horizontal slides concealed in the plow, which are run out and receive, hold, and transport the snow not loaded in the holders as the plow is pushed forward or is backed out of the obstruction.

10 6. The point j", constructed with a horizontal metallic cutting-bar at its base, and with a horizontal cutting-bar at its top, the space between the bars being plain perpendicular wedge-shaped surfaces.

15 7. In a plow structure provided with semi-circular snow-excavators, horizontal and perpendicular slides, a top deck, and top guard-

rail suited to be the place where the employed men stand and operate the several parts of the plow, and suited to the transportation of 20 the snow that falls on the deck in deep excavations or obstructions.

8. The bottom sheathing constructed beneath the working parts and axles of the structure in close proximity to the railway-track, with the track-wheels projecting but slightly through the sheathing, thereby providing a smooth bearing-surface on which the plow rests when derailed, and which aids in the return of the plow to the track. 25
